UNITED STATES PATENT OFFICE.

PETER P. LEOW, OF BOYNE CITY, MICHIGAN, ASSIGNOR OF ONE FORTY-FIFTH TO
JAMES S. LEOW, OF BOYNE CITY, MICHIGAN.

AUTOSLEIGH.

Application filed July 2, 1921. Serial No. 482,257.

To all whom it may concern:

Be it known that I, PETER P. LEOW, a citizen of the United States, residing at Boyne City, in the county of Charlevoix and State 5 of Michigan, have invented new and useful Improvements in Autosleighs, of which the following is a specification.

This invention relates to sleighs of the motor driven type and an object of the invention is to provide a sleigh which may be driven by an internal combustion engine or analogous prime mover, and one which may be guided in any direction desired and in which a planetary set of gears is embodied for transmitting power to the driving wheels.

Another object of this invention is to provide a motor sleigh as specified in which the driving wheels, which are carried by the 20 rear runner structure, may be moved vertically for regulating the action lengths of the spurs or grouters carried by their perimeters or to permit the said driving wheels to be moved out of operative position and further 25 to provide a novel form of mechanism for raising or lowering said driving wheels, the said mechanism being operated by a single feed screw to synchronously move, vertically, the driving wheels at the opposite 30 sides of the sleigh.

Another object of this invention is to provide a column associated with the steering column of the motor sleigh for operating said elevation regulating feed screw.

Other objects of the invention will appear in the following detailed description and in the accompanying drawings wherein:

Fig. 1 is a side elevation of the complete motor sleigh.

Fig. 2 is a longitudinal section through the rear or driving end of the motor sleigh.

Fig. 3 is a top plan of the rear or driving end of the motor sleigh.

Fig. 4 is a rear elevation of the motor sleigh showing the parts in section.

Fig. 5 is a top plan of the front or steering end of the motor sleigh.

Fig. 6 is a fragmentary section illustrating the steering mechanism.

Fig. 7 is a section on the line 7-7 of Fig. 2.

Fig. 8 is a diametrical section through one of the driving wheels.

Referring more particularly to the drawing the improved sleigh comprises front and

rear sections which provide respectively the steering and driving mechanism of the motor sleigh. The front runner section comprises front runners 1 supported and braced by the usual braces 2 and standards 3, the said runners being connected by a front axle 4 to which the front runners 1 are connected by means of yokes 5 at each end of the axle and ears 6 carried by the standards 3. The yokes 5 are pivotally connected to the vertically spaced sets of ears 6 so as to permit pivotal movement of the front runner 1 for steering the vehicle. The axle 4 is carried by the frame 7 which may be yieldably suspended by the usual type of leaf springs 8 similar to the manner of suspending the front end of the chassis of a motor vehicle. The front runners 1 are connected, for synchronous steering movement, by a suitable cross rod or steering rod 9 to which the arm 10 is connected by a ball and socket joint. The arm 10 is carried by the lower end of the steering post 12 upon the upper end of which a hand wheel 13 is mounted to facilitate manual rotation of the steering post 12 to guide the front runners 1.

The rear or propelling end of the motor sleigh comprises side runners 20 and 21 which are similar in construction, each comprising a housing structure 22 formed of suitable sheet metal and enclosing a propelling mechanism proper.

The propelling mechanism comprises drive wheels 23 and 24 carried by each runner which have circumferentially spaced spurs 25 on their perimeters for biting into the surface over which the sleigh is traveling. The driving wheels 23 and 24 are rotatably supported on suitable stub axles 26 which are in turn rotatably supported by the auxiliary housing 27 mounted within the housing 22. The wheels 23 and 24 each have a driving gear 28 carried thereby which meshes with an idler gear 29. The idler gears 29 mesh with other idler gears 30 which are driven by a gear 31 mounted upon the stub shaft 32. The stub shaft 32 has a gear 33 mounted thereon which meshes with a second gear 34 which is in turn driven by a pinion 35 mounted upon the rear drive shaft 36. The gear 34 is carried by a shaft 34' and remains stationary relative to the housing 27 during the vertical movement of the housing 27. As clearly shown in Fig. 4 of the drawing the drive shaft 36

extends across the rear end of the motor sleigh structure and is connected by means of bevel gears 37 with the driving shaft 38 which is in turn driven by the prime mover 5 or engine of the motor sleigh. The gears 29 and 30 are mounted to permit a planetary action relative to the gear 31 so as to maintain operative driving connection with the gears 28 under vertical adjustment of the 10 driving wheels 23 and 24. The housing 22 is slotted as shown at 39 to permit the movement of the gears 29 and 30 and also vertical adjustment of the driving wheels 23 and 24 without varying the elevation of the runners 15 40. The auxiliary housing 27 is mounted within the housing 22 for movement vertically therein and its end portions engage the ends of the housing 22 to guide its vertical movement. An arm 41 is connected to the 20 top or apex of each auxiliary housing 27 and the arms on each of the housings are connected in any suitable manner. Each pressure post or arm 41 is connected, by a link 43, with a pivotally mounted lever 44. 25 The lever 44 is pivotally supported upon a suitable bracket post 45 carried by the housing 22 and its short end is engaged by a roller 46 carried by the frame 47. Rollers 48 and 49 are also carried by the frame 47 30 and they engage against the guide rail 50. The frame 47 has a nut 52 thereon which is mounted upon a feed screw 53, supported by suitable bearings 54 on the frame 55 and the feed screws 53 at the opposite sides of 35 the motor sleigh frame are connected by a cross shaft 56 and suitable bevel gears 57. The cross shaft 56 is connected by bevel gears 58 to an operating rod 59 which extends forwardly and is rotatably supported 40 at its forward end by a suitable depending bracket 60. A bevel pinion 61 is mounted on the forward end of the rod 59 and meshes with a bevel gear 62 carried by the lower end of the column sleeve 63. The 45 sleeve 63 is rotatably mounted about the steering post 12 and has a hand wheel 64 thereon for permitting its manual rotation thereby allowing adjustment of the pressure applying members comprising the frames 47 and rollers 48 from the operator's seat of 50 the motor sleigh. As the pressure applying members are moved rearwardly, through rotation of the rod 59, the levers 44 are rocked upon their pivots forcing their rear 55 ends downwardly and applying downward pressure to the auxiliary housing 27 moving the driving wheels 23 and 24 downwardly and when the pressure applying members are moved forwardly the pressure 60 on the levers 44 is reduced and consequently the weight of the motor sleigh will cause the driving wheels 23 and 24 to move upwardly as far as permitted by the pressure levers 44.

Suitable guards 66 are provided for preventing the throwing of snow by the drive wheels 23 and 24 during their operation. As clearly shown in Fig. 2 of the drawing the rear runner structures 40 are formed of front sections 67 and rear sections 68 which curve and merge into the housing 22 being braced by suitable braces 69 to provide sufficient rigidity to the runners and during operation of the motor sleigh the front runners 1 and front portions 67 of the rear runners 40 will pack the snow sufficiently to provide a firm surface into which the spurs 28 will burrow for propelling the motor sleigh.

The rear runners are connected by a detachable cross brace 70 and the connecting bar 42 is connected to said cross brace 70 by means of suitable pins 71 riding through the cross brace and being braced in turn by diagonal braces 72.

Summing up, the operation of the improved motor sleigh is as follows:

The motor sleigh is steered by means of the steering wheel 13 through the medium of the cross rod 9 and steering post 12 to permit steering of the travel of the sleigh and it is propelled from an internal combustion engine or analogous prime mover through the medium of the rear drive shaft 36 and the sets of gearing carried by each of the rear runner structures 40. Varying conditions will require variation of the elevations of the drive wheels 23 and 24 and by rotating the hand wheel 64 the elevations of the drive wheels may be regulated as desired and made necessary by existing conditions. In traveling down inclines the drive wheels 23 and 24 may be moved out of operative position, that is, with the lowermost points of the spurs 25 above the under surfaces of the runners of the sleigh so as to permit the sleigh to coast down such inclines. When coasting the braking operation of the sleigh may be controlled by varying the elevation of the drive wheels, the weight of the sleigh causing it to stop.

It is, of course, to be understood that the invention may be constructed in various other manners and the parts associated in different relations and, therefore, I do not desire to be limited in any manner except as set forth in the claims hereunto appended.

Having thus described my invention what I claim is:

1. In a power driven sleigh, rear runner structures, housings carried by each of said runner structures and mounted for vertical movement, guide rails carried by the sleigh, feed screws, plates adjustably supported by said feed screws, rollers carried by said plates and engaging said guide rails, and means operated by movement of said

plate along said feed screw for raising or lowering said housing.

2. In a power driven sleigh, rear runner structures, housings carried by each of said runner structures and mounted for vertical movement, guide rails carried by the sleigh, feed screws, plates adjustably supported by said feed screws, rollers carried by said plates and engaging said guide rails, a pivotally supported lever normally resting on an incline, means connecting said lever and housings, a roller carried by said plate and engaging said lever for forcing the lever and housing downwardly upon movement of the plate along the feed screw in one direction and for forcing the housing upwardly upon movement of the plate along the feed screw in the opposite direction.

3. In a power driven sleigh, rear runner structures, housings carried by each of said

runner structures and mounted for vertical movement, guide rails carried by the sleigh, feed screws, plates adjustably supported by said feed screws, rollers carried by said plates and engaging said guide rails, a pivotally supported lever normally resting on an incline, means connecting said lever and housings, a roller carried by said plate and engaging said lever for forcing the lever and housing downwardly upon movement of the plate along the feed screw in one direction and for forcing the housing upwardly upon movement of the plate along the feed screw in the opposite direction, a plurality of driving wheels carried by said movable housing, an operating shaft, and a train of gears connecting said operating shaft and said driving wheels.

In testimony whereof I affix my signature.

PETER LEOW.
